[57] CLAIM

The ornamental design for tombstone memorial plaque and support bracket, as shown and described.

DESCRIPTION

FIG. 1 is a front elevational view of the tombstone memorial plaque and support bracket showing my new design; FIG. 2 is a left side elevational view thereof;

FIG. 3 is a top plan view thereof;

FIG. 4 is a rear elevational view thereof;

FIG. 5 is a left side elevational view thereof of a second embodiment of a tombstone memorial plaque and support bracket showing my new design, the right side is a mirror image;

FIG. 6 is a front elevational view thereof;

FIG. 7 is a top plan view thereof; and,

FIG. 8 is a rear elevational view thereof.

The broken line showing of the tombstone and plaque in FIGS. 1 and 2 is for illustrative purposes only and forms no part of the claimed design.
